NONREFILLABLE BOTTLE

Solomon Grauer, Brooklyn, N. Y.

Application November 25, 1932

Serial No. 644,172

6 Claims. (CL. 215—21)

The invention relates to bottle stoppers of the type which when inserted in a bottle will make this non-refillable. It has for its main object to provide a bottle stopper which can not be removed from the bottle when once inserted, and which positively prevents the introduction of any liquid or other substance into the bottle.

Another object is to provide a bottle stopper which may be adapted to make any type of bottle non-refillable without having to alter its shape or change its general appearance. A further object is to provide a bottle stopper, of simple and inexpensive construction, which can be inserted in a bottle as readily, and with practically the same means, as the ordinary cork now generally used.

These and various other objects and advantages will be readily understood from the following description and from the accompanying drawing of a preferred embodiment of the invention in which, however, modifications may be made without departing from the scope of the appended claims. In the drawing

Fig. 1 is a fragmental and cross-sectional view of a bottle with a stopper shown inserted therein; the view is taken on line 1—1, in Fig. 3;

Fig. 2 is a similar view showing the bottle tilted and the valve in the stopper in its open position;

Fig. 3 is a top view of Fig. 1;

Fig. 4 is a sectional top view taken on line 4—4 in Fig. 1; and

Fig. 5 is a side elevation of one of the parts of the stopper.

Referring now to all the views, simultaneously, the stopper comprises a body member preferably formed of two semicircular halves 10 and 11 on each of which a half-flange 12 is provided so that, when the two parts are assembled, a continuous flange is formed around the upper end of the body member. A concentric opening is formed in the body-member parts and in this a valve stem 13 is slidably mounted. A chamber 14 and an orifice 15 is likewise formed in the body-member parts.

The valve stem is provided with a relatively large valve disc 16 at its upper end and with a smaller valve disc 17 at its lower end. A plurality of grooves 18 are formed in the inner part of the body-member parts and extend from the chamber 14 to the top of these parts. The valve disc 16 closes these grooves, while the valve disc 17 closes the orifice 15. The body-member parts are held together, and secured tightly in the neck of the bottle 19, by a tubular member 20 made of resilient material, as for example cork. The

bottle is preferably made with an annular recess 21 against the bottom of which the flange seats. The top of the bottle may be constructed to hold a cap, or it may be externally threaded so that a threaded cap may be employed.

When the bottle is in its upright or normal position, the valve discs 16 and 17 close the upper ends of the grooves 18 and the orifice 15. The valve discs will remain in this position until the bottle is tilted to the approximate position shown in Fig. 2. In this position the valve stem, and consequently the valve discs, will slide and so uncover the grooves as well as the orifice. When in this position, its contents will freely flow through the opening 15, chamber 14, and, through some of the grooves 18, out through the recess 21 in the bottle. At the same time air is admitted to the interior of the bottle through some of the other grooves. When the bottle is restored to its normal position, the valve discs are likewise restored. When the bottle is tilted the lower valve disc acts as a detent and limits the movement of the valve stem.

The features which prevent the tampering with the contents of the bottle, as well as prevent it from being refilled, will now be explained. As the flange 12 is seated against the bottom of the recess 21 it is obviously impossible to push the stopper into the bottle. In addition, this flange prevents any destructive agent, such as an acid for example, which might be poured into the recess for the purpose of destroying the cork member, from reaching this. By making the recess of such a depth that the upper valve disc, even in its open position, does not extend beyond the top of the bottle and by making the valve disc but slightly smaller than the diameter of the recess, it is impossible to insert any tool or implement under the valve disc, either to lift it or to maintain it in its open position. Furthermore, if the upper valve disc is broken off, either wholly or in part, the lower valve disc will effectively seal the orifice 15 and prevent the introduction of any substance into the bottle.

While I have shown, and while I prefer to make the body parts as well as the valves and valve stem of porcelain and to make the body part in two pieces, it will be understood that any other material may be used and that the body part may be made in one piece. Likewise, holes drilled longitudinally through the body member may be substituted for the grooves shown. As shown in the drawing, both the upper and lower valve discs are seated when the bottle is in its normal position. There are instances when I prefer to

shorten the valve stem so that the lower valve disc does not cover the orifice 15 except when the upper disc is broken off. This arrangement prevents any liquid from remaining in the chamber 14 after the bottle has been tilted. In other cases it may not be necessary to use the lower disc as a valve, but only as a detent to limit the movement of the valve stem.

From the foregoing it will be seen that this device provides a simple, inexpensive and effective means for converting a bottle into a non-refillable bottle.

Having described the invention and its operation, what I claim as new and wish to protect by Letters Patent is:

10 1. A bottle stopper for preventing the refilling of a bottle; comprising a body member having an annular flange at its upper face insertable in a recess in the upper part of the neck of a bottle;

20 20 a plurality of passages formed longitudinally through said body member; a concentric opening formed in said body member; a valve stem, having a valve disc at its upper end and a detent at its lower end, slidingly mounted in said opening; and a resilient sleeve secured on the outside of said body member, below said flange, for securing the whole device in the neck of a bottle; said flange being of larger diameter than the sleeve to prevent this from being tampered with.

25 25 2. A bottle stopper for preventing the refilling of a bottle; comprising a body member having an annular flange at its upper face insertable in a recess in the upper part of the neck of a bottle; and a valve chamber in its lower end; an orifice 30 30 leading from the lower end of the body member to said chamber; a plurality of passages leading from said chamber to the upper face of the body member; an axial opening formed through the body member; a valve stem slidingly mounted 35 35 in said opening; a valve disc provided at the upper end of the valve stem for closing the upper ends of said passages; another valve disc provided at the lower end of the valve stem for closing said orifice; and a resilient sleeve secured 40 40 on the outside of the body member, below said flange, for securing the whole device in the neck of a bottle; said flange being of larger diameter than the sleeve to prevent this from being tampered with.

45 45 3. A bottle stopper for preventing the refilling of a bottle; comprising a body member having an annular flange at its upper face insertable in a recess in the upper part of the neck of a bottle; and a valve chamber at its lower end; an orifice 50 50 leading from the lower end of the body member to said chamber; a plurality of passages leading from said chamber to the upper face of the body member; an axial opening formed through the body member; a valve stem slidingly mounted 55 55 in said opening; a valve disc provided at the upper end of the valve stem for closing the upper ends of said passages; another valve disc provided at the lower end of the valve stem for closing the orifice if the upper valve disc is removed or the valve stem broken off; and a resilient sleeve secured on the outside of the body member, below said flange, for securing the whole device in the neck of a bottle; said flange being of larger diameter than the sleeve to prevent this from being tampered with.

60 60 4. A bottle stopper for preventing the refilling of a bottle; comprising a body member having an annular flange at its upper face insertable in a recess in the upper part of the neck of a bottle; and a valve chamber at its lower end; an orifice 65 65 leading from the lower end of the body member to said chamber; a plurality of passages leading from said chamber to the upper face of the body member; an axial opening formed through the body member; a valve stem slidingly mounted in said opening; a valve disc provided at the upper end of the valve stem for closing the upper ends of said passages; another valve disc provided at the lower end of the valve stem for closing the orifice if the upper valve disc is removed or the valve stem broken off; and a resilient sleeve secured on the outside of the body member, below said flange, for securing the whole device in the neck of a bottle; said flange being of larger diameter than the sleeve to prevent this from being tampered with.

member, below the said flange, for securing the whole device in the neck of a bottle; said flange being of larger diameter than the sleeve to prevent this from being tampered with.

4. A bottle stopper for preventing the refilling of a bottle; comprising a plural-parted body member having an annular flange at its upper face insertable in a recess in the upper part of the neck of a bottle and a valve chamber in its lower end; an orifice leading from the bottom of the body member to said chamber; a plurality of passages leading from said chamber to the upper face of the body member; an axial opening formed through the body member; a valve stem, formed integrally with a valve disc at each end, slidingly mounted in said opening; and a resilient sleeve secured on the outside of the body member, below said flange, for holding the body-member parts together and for securing the whole device in the neck of a bottle; said flange being of larger diameter than the sleeve to prevent this from being tampered with.

5. The combination with a bottle, having an annular recess in the upper part of its neck, of a bottle stopper; comprising a body member having an annular flange at its upper face and a valve chamber at its lower end; an orifice leading from the lower end of the body member to said chamber; a plurality of passages leading from said chamber to the upper face of the body member; an axial opening formed through the body member; a valve stem slidingly mounted in said opening; a valve disc provided at the upper end of the valve stem for closing the upper ends of said passages; another valve disc provided at the lower end of the valve stem for closing said orifice; and a resilient sleeve secured on the outside of the body member, below said flange, for securing the whole device in the neck of the bottle.

6. The combination with a bottle, having an annular recess in the upper part of its neck, and a bottle stopper; comprising a body member having an annular flange at its upper face and a valve chamber at its lower end; an orifice leading from the lower end of the body member to said chamber; a plurality of passages leading from said chamber to the upper face of the body member; an axial opening formed through the body member; a valve stem slidingly mounted in said opening; a valve disc provided at the upper end of the valve stem for closing the upper ends of said passages; another valve disc provided at the lower end of the valve stem for closing said orifice; the recess in the bottle being of sufficient depth to prevent the upper valve disc from projecting beyond the top of the bottle and the valve disc being of a diameter but slightly smaller than the diameter of the recess; and a resilient sleeve secured on the outside of the body member, below said flange, for securing the whole device in the neck of the bottle; said flange being of larger diameter than the sleeve to prevent this from being tampered with.

SOLOMON GRAUER.
